CLAIM

The ornamental design for a data gathering base unit or
the like, as shown and described.

DESCRIPTION

FIG. 1 is a top plan view of a data gathering base unit
or the like showing our new design;

FIG. 2 is a right side elevational view thereof, the oppo-
site side being a mirror image thereof;

FIG. 3 is a front elevational view thereof; and,

FIG. 4 is a top front right side perspective view thereof.

FIG. 2

FIG. 1

FIG. 3

FIG. 4
